UNITED STATES PATENT OFFICE.

AUGUSTUS ELLSWORTH BACHERT, OF ROBERTSDALE, PENNSYLVANIA.

DESIGN FOR A BOOK-PLATE.

No. 38,937.

Specification for Design.

Patented Dec. 10, 1907.

Application filed October 1, 1907. Serial No. 395,467. Term of patent 7 years.

To all whom it may concern:

Be it known that I, AUGUSTUS ELLSWORTH BACHERT, a citizen of the United States, residing at Robertsdale, in the county of Huntingdon and State of Pennsylvania, have invented a new, original, and ornamental Design for Book-Plates, of which the following is a specification, reference being had to the accompanying drawing, forming part thereof.

The figure is a plan view of the plate, showing my new design.

What I claim is:

The ornamental design for a book plate as shown.

AUGUSTUS ELLSWORTH BACHERT.
